CLAIM

The ornamental design for a holder for transporting and storing diskettes, as shown and described.

DESCRIPTION

FIG. 1 is a front upper left perspective view of a holder for transporting and storing diskettes showing my new design, the broken lines shown in FIGS. 1, 2, 3, and 6 being understood to represent perforations;

FIG. 2 is a rear lower right perspective view thereof;

FIG. 3 is a front elevational view thereof;

FIG. 4 is a left side elevational view thereof;

FIG. 5 is a bottom plan view thereof;

FIG. 6 is a rear elevational view thereof;

FIG. 7 is a right side elevational view thereof; and,

FIG. 8 is a top plan view thereof.
